UNITED STATES PATENT OFFICE.

ELI M. FRENCH, OF CHICAGO, ILLINOIS.

DESIGN FOR AN EGG-TESTING APPLIANCE.

56,060.

Specification for Design.

Patented Aug. 10, 1920.

Application filed October 24, 1919. Serial No. 333,133. Term of patent 7 years.

To all whom it may concern:

Be it known that I, ELI M. FRENCH, a citizen of the United States, residing at Chicago, in the county of Cook and State of Illinois, have invented a new, original, and ornamental Design for an Egg-Testing Appliance, of which the following is a specification, reference being had to the accom-

panying drawing, in which a perspective view of the design is shown.

I claim:—

The ornamental design for an egg testing appliance, as shown.

In testimony whereof I affix my signature.

ELI M. FRENCH.
